ACTUATING MECHANISM FOR CALCULATING MACHINES

Application filed May 27, 1925, Serial No. 33,156, and in Germany March 5, 1924.

The invention relates to actuating and printing mechanisms for adding and duplex adding machines, cash registers and the like. In such machines, the counters are operated by adjusting members controlled by the keys. Heretofore, said adjusting members were initially released for action through a movement of the main drive shaft and were then actuated or driven through their range of movement by springs.

The main object of the present invention is to provide a positive drive for said adjusting members, which according to the present invention consists of two members: one being an actuating member and the other a coupling member. Both members are connected by a pawl which is adapted to couple the members with the drive shaft subsequent to a relative movement between said members which movement takes place at depression of a key. The members are uncoupled from the drive shaft when the actuating member is arrested by a key-controlled swinging lever, whereby reverse movement between the actuating and coupling member is produced.

Another object is the positive actuation of the printing mechanism, the characters or type being carried by said coupling members.

Another object of the invention is the control of the adjusting members of the lower digits of a decimal figure which adjusting members are, according to the invention, automatically swung out into a position in which the zero type is brought into printing position.

A further object of the invention is to positively arrest the adjusting member in proper position prior to the printing operation and to hold said member in said position during the printing operation.

Still another object of the invention resides in the provision of means for tensioning springs, which actuate the pressure hammer of the printing mechanism, prior to the release of said hammer, and for releasing the spring tension thereafter, to enable the hammer to return to initial position by gravity.

Other objects of the invention will appear more fully hereinafter.

The invention consists furthermore in the construction, combination, location and rela-

tive arrangement of parts, all as will be more fully hereinafter set forth, as shown in the accompanying drawings and finally pointed out in the appended claim.

An embodiment of the invention is illustrated in the accompanying drawings, in which:

Fig. 1 is a vertical section through a decimal figure of a duplex adding machine or cash register;

Fig. 2 shows in front view some of the adjusting members and means for bringing the adjusting members of the lower digits into zero printing position;

Fig. 3 is a fragmental sectional view similar to Fig. 1 with a key depressed and the other parts in different positions;

Fig. 4 shows on an enlarged scale an actuating member and its coupling member coupled to the drive shaft.

The main drive shaft 1 is positively connected with the shaft 3 by means of a link 2, said link connecting crank disc 1^a on shaft 1 and crank 2^a on shaft 3. (Fig. 2). Rotatably supported on the shaft 3 are a series of actuating members 4, one actuating member being provided for each bank of keys. Each actuating member has on its upper edge stops 1 to 9 arranged in step formation and adapted to coact with an abutment 7^a of a swinging lever 7. One swinging lever 7 is provided for each bank of keys and is controlled by the keys t', t², t³-t⁹. Each lever 7 is adapted to be swung through a different range of movement corresponding to the denomination of the key actuated. Coupling member 4^a is coupled with actuating member 4, by means of a pawl 6 carried by the coupling member. The pawl 6 has an arm 6^a extending into a recess of the actuating member 4, the recess being so formed that its opposite surfaces engage the opposite surfaces of the arm to rock the pawl whereby, upon relative rotation between members 4 and 4^a, the pawl 6 is moved into and out of engagement with an abutment 5 formed

on a collar 40 which is fixed to the shaft 3. A spring 8 tends to move the members 4 and 4^a in such a manner as to cause the pawl 6 to engage the abutment 5 as shown in Fig. 4, where the spring 8 has moved the member 4 with

respect to the coupling member 4^a an amount indicated at *r*, which is sufficient to bring the pawl 6 into engagement with the abutment 5. A latch 9 is provided on each adjusting member and is actuated by a spring 9^a and cooperates with abutment levers 10 and 11 in such a manner that in position of rest and in the zero (0) positions of the actuating member, the latter is rotated with respect to its coupling member so far, that pawl 6 is held out of engagement with the abutment 5. The swinging movement of the abutment levers 10 and 11 is controlled by the key *t* of the corresponding decimal order. If no key is moved, the corresponding adjusting member remains in its position of rest.

The abutment levers 10, 11 are actuated from the main drive shaft 1 by means of the cam 1^a having a cam groove 1^b on one side thereof. A cam follower 12^a, projecting in to said groove, is pivoted to the end of a lever 12, swingably mounted on shaft 13. The other end of lever 12 is connected to a lever 15, rigidly fastened on a shaft 14. Thereby shaft 14 is oscillated at each revolution of the main drive shaft. Three levers 10, 11, 16 are provided for each key-actuated swinging lever 7. The lever 16 is rigidly mounted on shaft 14 and between the U-shaped bearing portions of levers 10 and 11 (see Fig. 2), which are loosely mounted on shaft 14. The end of each lever 16 carries an adjusting screw 16^a normally in engagement with a bent portion 11^b of lever 11. The upper end 35 of each lever 11 is connected by a spring 17 to a stamping loosely mounted on shaft 13, whereby the bent portion 11^b is normally kept in engagement with screw 16^a. The upper end of each lever 11 has a bent portion 11^c cooperating with an abutment 7^b on the corresponding lever 7 for the purpose of preventing swinging movement of lever 11, when its corresponding lever 7 is in its normal position of rest, in other words, not depressed by 45 a key (see Fig. 1). At depression of lever 7, its cooperating lever 11 is free to move, and spring 17 causes lever 11 to follow lever 16 during the forward oscillation of the latter. The lower end of lever 11 has a hook-shaped 50 portion, adapted to engage latch 9 (Fig. 3), normally held in its position of rest by lever 10 (Fig. 1). Lever 10 is U-shaped. One shank 10^a of the U-shaped lever 10 is mounted on shaft 14 between lever 16 and lever 11. The other shank is mounted outside of levers 55 11 and 16 (Fig. 2). By depressing a swinging lever 7, the corresponding lever 11 is permitted to follow the swinging motion of lever 16, the latter being rigidly fastened on the oscillating shaft 14. The corresponding lever 10 is taken along by the bent portion 10^c overlapping arm 11^a, and both levers 10 and 11 are swung out of the path of latch 9.

The advance movement of actuating member 4 relative to coupling member 4^a per-

mitted by release of latch 9 and caused by spring 8, couples both members 4 and 4^a to shaft 3, and the rotary movement of both members is finally arrested by the projection 7^a of lever 7, cooperating with the stepped stops of actuating member 4. Furthermore, levers 10 of the lower decimal orders are swung out to permit the movement of the actuating members 4 of the lower orders from the position shown in Fig. 1 to the position shown in Fig. 3, so as to bring the zero type into printing position (Fig. 3). For this purpose, the levers 10 are provided with bent portions 10^b projecting across the levers 11 and the shanks 10^a of lever 10 of the next lower order, as illustrated in Fig. 2. In this manner, all the levers 10 corresponding to the lower decimal orders are swung out of the path of the latch 9, and the corresponding actuating members are arrested by contact of latch 9 with the hooked portions of levers 11. To prevent transmission of this initial movement of the adjusting members to the counters, the connecting links 18 are provided with slots 18^a at their connecting points with the levers 34. The return movement of levers 10, 11, 16 takes place shortly after the actuating members 4 have been returned. Lever 16 returns lever 11 by engaging the bent portion 11^b, and lever 10 is yieldingly returned by a spring 11^d connecting the bent portion 11^b of lever 11 and lever 10. Each spring 17 of the higher decimal orders has to be strong enough to overcome the total pressure exerted by the springs 11^d belonging to all the lower decimal orders.

For returning the actuating member to initial position, a second abutment 5^a is provided on collar 40 for each decimal order. This abutment 5^a cooperates with an abutment 22 of the corresponding actuating member and thereby returns the actuating member to a point at which the latch 9 again engages lever 10. The main drive shaft 1 and its cam 1^a completes one revolution at each forward and backward oscillation or excursion of the shaft 3. The dead center position of the drive shaft is illustrated in Fig. 1 by the dotted line connecting the pivot of crank arm 2^a and the center of the drive shaft 1. Before reaching its position of rest, shaft 1 passes beyond this dead center position (as illustrated in Fig. 1). The extra movement of shaft 1 produces a slight forward movement of shaft 3, so that abutment 5^a is spaced from the abutment 22 an amount permitting an advance movement of member 4 with respect to member 4^a when latch 9 is released at the beginning of the next excursion of shaft 3, said movement being sufficient to swing pawl 6 into coupling engagement with abutment 5. The crank arm 2^a is longer than the lever arm of the crank disc 1^a, as shown in Fig. 1. The amplitude of oscillation of shaft 3 is determined by the length of said crank arm 2^a.

In case it is desired that the adjusting member shall also carry the type characters 19, they may be arranged on the coupling member 4^a, which is furthermore provided with a notched segment 4^b, the notches thereof being spaced to correspond with the spacing of the type characters. A detent 20 coacts with said notched segment and is carried by a swingable arm 20^a which is positively coupled by means of a connecting link 21 with the releasing device 22, of the pressure hammer 23 in such a manner, that, before releasing the hammer, the detent 20 is swung into mesh with the proper notch of the segment 4^b, and thereby keeps the type in correct printing position.

Arm 20^a is loosely mounted on shaft 20^b and has integrally formed therewith two other arms 20^c, 20^d. Arm 20^d is connected to the releasing device 22 of the pressure hammer 23 by means of the link 21, having a slot connection with the device 22. Arm 23 cooperates with a cam 25 by means of a cam follower 20^f. The cam follower is pressed against the cam 25 by a spring 20^e (Fig. 1). The cut-out portion of cam 25 permits swinging movement of the arms 20^a, 20^c, 20^d, whereby detent 20 is brought into mesh with the proper notch of segment 4^b, and whereupon the hook 26 of the release means 22 is moved out of engagement with the hammer 23.

The hammer 23 is actuated by a spring 33 which is tensioned previously to the actuation of the hammer by the following device: A cam 27 is mounted next to cam 25 on the main drive shaft 1. Cam 27 cooperates with a lever 28 swingably mounted on shaft 13, and connected by a link 29 to a crank lever 30. The crank lever 30 is connected by a link 31 to a lever 32 carrying the leaf spring 33. After tensioning the spring 33 by swinging lever 32 to the left (Fig. 3), the hammer is released, whereupon cam 27 moves out of contact with lever 20^a, thereby releasing the spring 33, and permitting return of hammer 23 to initial position by gravity. In said position, the hammer is engaged by the member 26 which is also returned to initial position by return movements of the levers 20^a, 20^c, 20^d.

The coupling member 4^a transmits its swinging movement by means of links 18, 34, 35, a segmental gear 36 and an intermediate gear 37 to the counters 38 and 39 respectively as described in my copending application Serial No. 26,875, filed April 30, 1925, for duplex adding machines and cash registers.

I claim:

In a machine of the class described, the combination of a drive shaft having a fixed excursion, a coupling member mounted on said drive shaft and rotatable with respect thereto, a collar, having two abutting surfaces, fixed to said drive shaft adjacent said coupling member, a pawl pivoted to said

coupling member and adapted to be moved into and out of locking engagement with said collar, and an actuating member loose on said shaft, said actuating member having an abutment member fixed thereto and also having a pair of surfaces engaging said pawl whereby relative rotation between the actuating member and the coupling member causes said surfaces to move the pawl into and out of engagement with said collar, said relative rotation being limited by the abutment member striking the abutting surfaces of the collar.

In testimony whereof I affix my signature.

ERNST KASSNER.
